UNITED STATES PATENT OFFICE

2,539,069

REMOVABLE LABEL HOLDER FOR BOOKS

William Galeone, Livonia Township, Wayne County, Mich., assignor to Office Products, Inc., a corporation of Michigan

Application October 30, 1947, Serial No. 782,972

1-Claim. (Cl. 40—16)

2

a removable label holding member of the present invention attached thereto;

Fig. 2 is an enlarged perspective view of the label holding member illustrated in Fig. 1, shown 5 from the front side thereof;

Fig. 3 is a perspective view of the label holding member illustrated in Fig. 2, as viewed from the rear thereof, and

Fig. 4 is an enlarged sectional view of the 10 structure illustrated in Fig. 1, taken on the line 4—4 thereof.

In the figures, a book 10 is illustrated which may be a loose-leaf type having rings 11 for supporting a plurality of removable sheets 12. Side 15 covers 13 and 14 are provided on the book in extension of the back 15 thereof. The label holding member 16 embodies a U-shaped frame member 17 made of wire, having a bottom web portion 18, two side legs 19 and reversely bent 20 clamping arms 21. The ends of these arms are arcuately formed at 22 for engagement with the lower portion of the label holding element 23. The label holding member 23, as herein illustrated, comprises a metal stamping having the

25 side edges flanged at 24 and having the front face 25 provided with a window 26. The flanges are bent over the legs 19 of the wire frame member 17, with the flanges spaced from the body portion 25 so as to form slides for the label 27.

30 The label is limited in its downward movement by engagement with the web portion 18, and the label holding member 23 is prevented from moving downwardly from the frame member 17 by the crimp 28 provided in the flanges 24 above the 35 web portion 18. It will be noted that the engagement of the arcuate portions 22 of the clamping arms 21 with the label holding member 23 is below the center thereof so as to draw the holding member flush against the book back 15 when the 40 member is secured to the book, as illustrated in Figs. 1 and 4.

When attaching the holder to the book, the label is first inserted in the slides formed by the bent flanges 24 and thereafter the clamping arms 45 17 are inserted over the book back 15 directly adjacent to the covers 13 and 14 and forced downwardly until the webs 29 joining the legs 19 to the clamping arms 21 engage the top of the book back. As pointed out above, the arcuate 50 portions 22 of the arms draw the label holding member 23 flush against the back cover of the book and from all appearances the removable label holder forms a permanent part of the book back. While the frame member 17 is herein illustrated as having a label holding member 23

This invention relates to removable label holders for books and the like, and particularly to a label holder having a window through which the label is visible and arms which support the holder on the back of a book.

The present label holder is constructed of a wire frame member and a label holding member which are secured together. The wire of the frame member is bent in U shape, having the ends reversely bent and arched at the ends in engagement with the U-shaped portion to form clamping arms. The label holding member is stamped from sheet metal having two side flanges which are bent over the arms of the U-shaped frame and spaced from the main portion of the stamping to form a slide for the label. The web of the U-shaped portion of the wire frame forms a stop for limiting the downward movement of the label in the holder. The flanges of the stamping are bent over the web to prevent the label holding member from sliding downward of the frame member.

The holder is attached to the book by sliding the clamping arms downwardly over the back of the book in the spaces between the leaves and the cover, with the label holding portion disposed on the outside of the back at the top of the book. The arched portions of the clamping arms engage the book back below the center of the holding member to draw it against the back.

Accordingly, the main objects of the invention are: to provide a label holder which is attachable to the back of a book and clamped thereagainst; to provide a holder made of a frame element of wire bent in U shape forming the web and two legs, the legs of which are reversely bent upon themselves to form clamping arms which draw the label holding member attached to the frame element against the surface of the book back; to form a label holding member of a stamping having a window therein and side flanges which are bent over the legs of a U-shaped wire frame member to form a slide for the label which is located in the holder by the web of the frame member at the bottom thereof, and, in general, to provide a removable label holder for a book which is simple in construction and economical of manufacture.

Other objects and features of novelty of the invention will be specifically pointed out or will become apparent when referring, for a better understanding of the invention, to the following description taken in conjunction with the accompanying drawing, wherein:

Figure 1 is a perspective view of a book having

attached thereto by the bending of the flanges 24 over the legs 19 thereof, it is to be understood that the holding member could be made of materials other than metal, such as plastic, and that the plastic material could be applied in the same manner as the sheet metal member herein illustrated and described or by being molded directly to the frame member.

What is claimed is:

A label holder including, in combination, a body portion made from a sheet of material having an opening therein through which a label may be viewed, the sides of said body portion being reversely bent backwardly over the main body portion and spaced therefrom, wire means extending downwardly in the space between said reversely bent side portions and the body portion and crimped thereabout and fixed therein against upward movement, the space between the side portions and the body portion inwardly of the

wire means forming slides for receiving a label, the projecting ends of the wire means being reversely bent to form supporting arms for the holder.

WILLIAM GALEONE.
